INTERNAL-COMBUSTION ENGINE

Joseph Barraja-Frauenfelder, Swarthmore, Pa., assignor to Sun Shipbuilding & Dry Dock Company, Chester, Pa., a corporation of Pennsylvania

Application February 3, 1937, Serial No. 123,930

3 Claims. (Cl. 123—51)

This invention relates to an improvement in internal combustion engines and more particularly to an improvement in opposed piston engines of the fuel injection or Diesel type.

5 Heretofore in opposed piston engines of the fuel injection or Diesel type disadvantage has been noted from the fact that lubricating oil working up the side rods which connect the outer piston with the crank shaft is thrown off against 10 the outer working piston at the beginning of its outer stroke and by the piston carried into the working cylinder wherein it is lost.

Again, disadvantage is found in opposed piston engines of the type indicated wherein a 15 scavenging air pump is provided for operation by connection of the scavenging air pump piston with the outer working piston, since lubricating oil working up the side rods, which are encompassed by the scavenging air pump cylinder, is 20 thrown from the rods to the wall of the scavenging air pump cylinder from where it works through into the suction side and is consumed with the scavenging air.

Various efforts have been made to avoid the 25 loss of lubricating oil which, escaping from the crank pins, tends to work up the side rods. Thus, for example, the side rods have been equipped with deflectors with the idea of stopping the travel of the oil up the rods and causing it to 30 return to the crank case. However, such means have proved unsatisfactory, since it has been found that the oil will work around the deflectors and continue up the rods to be thrown off from the upper ends of the rods against the working 35 piston and the scavenging air pump cylinder with resultant loss.

Now, in accordance with this invention means 40 are provided whereby oil working up the side rods and being thrown off from the upper end thereof will be prevented from reaching the working piston and hence from being carried into the working cylinder and whereby the passage of oil which may be thrown against the wall of the scavenging air pump cylinder will be prevented from 45 working up past the scavenging air pump piston and hence from entry into the working cylinder with the scavenging air.

More particularly, in accordance with this 50 invention the outer end of the working piston is provided with a skirt or deflector arranged to receive oil thereon from the ends of the side rods and prevent its reaching the surface of the working piston, while, at the same time, the scavenging air piston is provided with a trunk working 55 on the wall of the scavenging air cylinder,

of such length with respect to the stroke of the piston that oil thrown from the rods against the wall of the scavenging air cylinder will not work by the piston.

Having indicated in a general way the nature 5 and purpose of this invention, I will now proceed to a detailed description thereof with reference to the accompanying drawing in which a preferred embodiment is illustrated and in which the single figure is a sectional view of an opposed 10 piston engine of the fuel injection or Diesel type in accordance with this invention.

In the single figure, 1 indicates the frame of the engine in which is supported the usual crank 15 shaft. 4 indicates a working cylinder in which the usual opposed pistons operate and of which the outer piston 6, controlling the scavenging air ports 9, which are in communication with the usual scavenging air receiver 10, is shown. The inner end of the working cylinder is provided 20 with the usual exhaust ports controlled by the inner of the two opposed working pistons.

The outer working piston 6 is connected with the crank shaft by means of side rods 12, 12, 25 through the medium of pin or cross head 13.

Mounted on the frame 1 is a scavenging air pump cylinder 14, of a diameter such as to accommodate the side rods 12, 12 and pin or cross head 13, provided with a head 25 connected with scavenging air receiver 10 through puppet valves 30 15, 15 and in communication with a fresh air chamber 16 open to the atmosphere through an aperture 17 through puppet valves 18, 18. The several puppet valves are provided with springs, as shown, for closing them.

A scavenging air pump piston 19, adapted to 35 work in the scavenging air pump cylinder 14, is directly connected to the outer end of the outer piston 6.

At the outer end of the outer piston 6, beneath 40 the bearings 20, for the support of the pin or cross head 13, is a depending, annular flange or skirt 21, of a diameter in excess of the outer diameter of the working cylinder and of a depth such as to extend substantially below the upper 45 ends of the side rods 12, 12 at their point of connection with the pin or cross head 13. The diameter and height of the depending, annular flange or skirt 21 is such that at the lower dead center position of the outer piston the flange or skirt will embrace the outer end of the working cylinder, as shown in dotted lines in the drawing.

The scavenging air pump piston 19 is, in general, of any desired construction and is directly 55

connected with the outer working piston 6 in any desired manner. The scavenging air pump piston is, however, particularly characterized by the fact that its trunk 19', provided with a single compression ring 22, is of a height to provide a long bearing surface with the wall of the scavenging air pump cylinder 14 and is of a height from $\frac{1}{2}$ of the length of its stroke to in excess of the length of its stroke. When the piston is 10 in its lower dead center position, the lower portion of the trunk extends beyond the wall of the scavenging air pump cylinder, as shown in dotted lines in the drawing.

The operation of the engine embodying this 15 invention will, it is believed, be readily understood. In general, the engine operates through the usual cycle and in the usual manner for engines of the fuel injection or Diesel type. That is to say, on the inner or compression stroke of 20 the working pistons air is compressed between them, fuel is injected into the cylinder between the pistons through a fuel injection device entered in the threaded aperture 23 at the proper time, the pistons are forced apart by expansion of the 25 fuel on combustion, the burned gases are exhausted through the exhaust ports 7, which are opened by the inner piston 5, and the working cylinder is scavenged by scavenging air entering through the scavenging air ports 9, which are 30 opened by the outer piston 6 after opening of the exhaust ports.

The work upon the outer working piston 6 is transmitted to the crank shaft through the pin or cross head 13 through the side rods 13, 13, while 35 the work upon the inner piston 5 is transmitted to the crank shaft through the connecting rod 11.

The necessary scavenging air is provided by 40 the operation of the scavenging air piston 19 in the scavenging air cylinder 14, supply of fresh air being drawn by the piston through puppet valves 18, 18 and the air compressed by the piston being discharged through puppet valves 18, 18 into the scavenging air receiver 10, from which 45 it passes to the working cylinder through the scavenging ports 9.

In the operation of the engine, assuming, for example, as is usual, that the crank pins are lubricated by forced speed of oil through passage 50 formed in the crank shaft, a certain amount of oil will escape from the ends of the crank pin bearings and a portion thereof will be picked up by the side rods 13, 13. Oil picked up by the side rods will work itself along the surface 55 of the rods until it reaches the ends thereof adjacent their connection with the pin or cross head 13, at which point the oil will be thrown off the rods.

Oil, as indicated at x, thrown off from the ends 60 of the rods will in part impinge against or be caught by the depending, annular flange or skirt 21 at the outer end of the outer working piston and will, in the reciprocation of the piston, drip therefrom clear of the surface of the piston and 65 of the working cylinder, since the diameter of the flange is such that it is considerably in excess of the outer diameter of the piston and in excess of the outer diameter of the working cylinder. Since the depending flange or skirt 21 ex- 70 tends below the outer end of the working cylinder in the lower dead center position of the outer working piston, oil caught by the outer face of the flange will be positively prevented from entering the working cylinder in the change in the 75 direction of motion of the outer piston from an

inward direction to an outward direction with respect to the working cylinder when force will be exerted upon oil carried on the outer face of the flange or skirt 21 tending to throw it off the face or the flange of skirt as shown at x'. 5

Again, oil, as shown at y, thrown off from the ends of the rods 13, 13, will be thrown upon the surface of the scavenging air pump cylinder 14. Due to the height of the trunk of the scavenging air pump piston, such oil will not be able to work 10 by the piston in the downward stroke thereof and will be carried below the wall of the scavenging air pump cylinder when the piston reaches its lower dead center position. As a result, not only will oil thrown against the scavenging air pump 15 cylinder be prevented from passing the piston due to the length of its trunk, but such oil will be discharged from the inner end of the scavenging air pump cylinder due to the extension of the 20 trunk of the scavenging air pump cylinder when the piston is in lower dead center position, as shown at y'.

The operation of the engine embodying this invention, with respect to the avoidance of loss of 25 oil working by the side rods through entry thereof into the working cylinder, directly or through the scavenging air pump, will, it is believed, be entirely clear from the above description in connection with the drawing and, in particular, with reference to the showing in dotted lines of the 30 outer working piston and the scavenging air piston.

It will be understood that the embodiment of 35 this invention, as above described in detail, is so described for the purpose of illustration only and it is to be understood that various modifications in detail as involved in the above description may be made without departing from the scope of 40 this invention, which is contemplated as capable of various embodiments other than that as above described.

What I claim and desire to protect by Letters Patent is:

1. In an internal combustion engine of the 45 opposed piston type, in combination, a working cylinder, an outer working piston in said cylinder, side rods connected to the outer working piston and an annular flange on said outer piston extending inwardly from adjacent the points of connection of said piston with said side rods, 50 said annular flange being of a diameter greater than the outside diameter of the end of the working cylinder and the flange being of such length as to embrace the end of the working cylinder when the outer working piston is in inner 55 dead center position.

2. In an internal combustion engine of the 60 opposed piston type, in combination, a working cylinder, an outer working piston in said cylinder, side rods connected to the outer working piston, a scavenging air pump cylinder mounted adjacent the outer end of the working cylinder and of a diameter to embrace said side rods, a scavenging air pump piston within the scavenging air pump cylinder, the trunk of said piston working on the wall of the scavenging air pump cylinder being of a height of from one-third of the length of its stroke to in excess of the full length of its stroke and an annular flange on said outer piston extending inwardly from adjacent the 70 points of connection of said piston with said side rods, said annular flange being of a diameter greater than the outside diameter of the end of the working cylinder and the flange being of such length as to embrace the end of the working 75

cylinder when the outer working piston is in dead center position.

- 5 3. In an internal combustion engine of the opposed piston type, in combination, a working cylinder, an outer working piston in said cylinder, side rods connected to the outer working piston, a scavenging air pump cylinder mounted adjacent the outer end of the working cylinder and of a diameter to embrace said side rods, a
10 scavenging air pump piston within the scavenging air pump cylinder, the trunk of said scavenging

air pump piston working on the wall of the scavenging air pump cylinder being of a height of from one-third of the length of its stroke to in excess of the full length of its stroke and arranged to extend beyond the end of the wall of 5 the scavenging air pump cylinder when the piston is in lower dead center position whereby oil thrown on the wall of the scavenging air pump cylinder is prevented from by-passing the scavenging air pump piston.

10 JOSEPH BARRAJA-FRAUENFELDER.
